UNITED STATES PATENT OFFICE.

MITCHEM WEBB OFFUTT, OF PHILADELPHIA, PENNSYLVANIA.

APPLIANCE FOR GAS-MAINS.

No. 891,854.

Specification of Letters Patent.

Patented June 30, 1908.

Application filed August 21, 1907. Serial No. 389,454.

To all whom it may concern:

Be it known that I, MITCHEM WEBB OFFUTT, a citizen of the United States, and resident of Philadelphia, in the county of Philadelphia and State of Pennsylvania, have invented certain new and useful Improvements in Appliances for Gas-Mains, of which the following is a specification.

It is frequently necessary to cut gas mains for various purposes, among which reference may be made to the insertion of T and other special fittings and devices. In practice gas is always in the mains and therefore and more particularly when the mains are of relatively large size it is essential that the cut portions of the main be closed, as otherwise workmen and others engaged in working in the trench, which has been dug for obtaining access to the mains, are subject to danger 20 from asphyxiation and the deleterious effects of inhaling gas.

In cutting a gas main it is customary to make two openings in its wall upon opposite sides of the place where the cut is to be. There is inserted through the opening farthest away from the place where the cut is to be a device called a gas stopper upon which reliance is had for preventing the escape of gas. Through the opening nearest the place where the cut is to be there is inserted a gas bag upon which little reliance is had and which is intended to stop the comparatively small amount of gas which may pass the gas stopper, even when it is properly adjusted or adjusted as well as was heretofore possible. However, if the gas stopper fails, the gas bag will not hold the pressure and the result is that gas escapes in large volume into the trench where, in many instances, it overcomes the workmen and even asphyxiates them, and if it should be impossible to stop the flow of gas from the break in the main, it would result in putting the district or town out of gas.

A gas stopper usually comprises a pair of springs hinged together at their ends and provided with hand rods pivoted to the hinges. Secured to the springs is a diaphragm and there is usually a leather covering on the springs. An example of such a device is described in Letters Patent No. 591,271, dated October 5th, 1897, to P. Goodman. The gas stopper is inserted through one of the openings, as has been described, and its hand rods are then manipulated so as to expand the springs and diaphragm, which they carry,

into generally circular form in contact with the inner wall of the pipe. Reliance is had upon friction to hold the stopper in place. However, it frequently happens that the stopper slips by reason of several causes, among which may be mentioned the jarring of the pipe by reason of the blows which it receives during the cutting or other operations, the falling of clods or lumps of dirt from the trench onto the pipe or onto the stopper rods which project through the opening made in the pipe, and the unstable position of the stopper, which must of necessity be placed in inclined position with its top part nearer to the place where the cut is to be made than its bottom part. If the stopper were not thus placed it and its operating rods would assume such a position that it could not be withdrawn from the opening in the wall of the pipe, as is well understood by those skilled in the art.

The principal object of the present invention is to provide for holding the stopper in fixed and immovable position within the pipe, notwithstanding gas pressure and other loosening causes to which it is exposed, thereby guarding the workmen and others on the job against danger from being overcome or asphyxiated.

The best, but not the only, embodiment of the invention now known to me is illustrated in the accompanying drawings, in which

Figure 1, is a view principally in section illustrating a stopper embodying features of the invention. Fig. 2, is a perspective view illustrating an appliance embodying my invention and adapted for use in connection with the stopper illustrated in Letters Patent No. 591,271, and Fig. 3, is a top or plan view illustrating one of the devices shown in Fig. 1.

According to my invention the stopper is provided with a fastening device for attachment to the pipe and with a rod or stay and there are means coöperating with the rod or stay and fastening device whereby the stopper is pressed and firmly held in position.

In the drawings the rods H and I and the stopper D, correspond, generally speaking (although without intending to limit my invention) to the parts with similar letters shown in said Letters Patent 591,271. 1, is the main or gas pipe in the wall of which are formed openings 2 and 3, and 4, indicates the cut.

I have illustrated the arrangement on one side of the cut and that on the other side is

similar to it. The stopper D is put into the pipe through the opening 3, in generally vertical position and then brought into inclined position as shown by means of the rods H 5 and I in the well understood manner which is set forth in said Patent No. 591,271.

Having described so much of an old device as is necessary for an understanding of my invention, I will now proceed to describe 10 the same.

The particular embodiment of the invention shown in the drawings is adapted for application to the stopper manufactured in pursuance of Letters Patent 591,271, with- 15 out alteration therein and I will proceed with a description of it.

5, is a fastening device for attachment to the pipe. It is shown as a hook adapted to engage the pipe 1, at the rim of the opening 20 3, and it is mounted on a shaft 6, by means of a thread - and - screw connection. The shaft 6, is provided with a slideable claw 7, adapted to engage the rod I, or more accurately the handle on the end thereof.

25 8, is a collar adjustable on the shaft 6 and provided with a set screw for holding it in place. The end of the shaft 6 is provided with a handle 9. After the stopper D has been adjusted to place manually by means of 30 the rods H and I, in the ordinary way, the shaft is arranged in the position shown and by means of the described adjustments and by turning the shaft 6, if necessary, the top portion of the stopper D is firmly pressed up 35 against the inside of the pipe and is then held fixed and immovable in that position. This is accomplished because by turning the shaft, the distance between the hook 5 and claw 7 is shortened as much as may be necessary. 40 Ordinarily it is sufficient to push and hold the top part of the stopper D, as has been described, because the bottom part of the stopper is unlikely to slip, the friction being sufficient to hold it. However, if desired 45 use may be made of a fastening device for

engaging the pipe and holding the bottom part of the stopper. 10, is such a device and it is shown to comprise a plate adapted to overlie the opening 3 and having a notch 11 provided with an open part through which 50 the shank of the rod H may be inserted and adjusted and provided with a set screw 12, for engaging the rod H and clamping it in respect to the plate 10 and permitting of its adjustment. 55

What I claim is.

1. The combination of a gas stopper and device adapted to engage one side wall of a pipe, and means for exerting pressure between the device and one point on the rim of 60 the stopper to vary the degree of inclination of its position, substantially as described.

2. The combination with the top rod of a gas stopper of a fastening device adapted to engage one side wall of a pipe, and means 65 interposed between the fastening device and the rod of the stopper for shifting the latter in respect to the former, substantially as described.

3. In a gas stopper of the inclined variety 70 the combination with the top rod of the stopper, of a fastening device adapted to engage a pipe, and means interposed between the fastening device and the rod of the stopper for shifting and holding the latter in inclined position, substantially as described. 75

4. A device for use in connection with gas stoppers comprising a shaft provided with a hook having screw and thread connection therewith, a claw movable on said shaft, and a collar adjustable on the shaft and adapted to position the claw, substantially as described. 80

In testimony whereof I have hereunto signed my name.

MITCHEM WEBB OFFUTT.
